(57) CLAIM

The ornamental design for a neck guard with flap, as shown and described.

DESCRIPTION

FIG. 1 is a perspective view of a neck guard with flap, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of the neck guard with flap of FIG. 1, shown in condition of use for clarity of disclosure. The broken lines (dashed) shown in FIGS. 1-8 represent unclaimed portions of the neck guard with flap and form no part of the claimed design. The broken lines (dot-dashed) shown in FIG. 8 represent environmental matter and form no part of the claimed design.
